UNITED STATES PATENT OFFICE.

LUDVIG A. LARSON, OF SUMMIT, SOUTH DAKOTA.

INTERNAL-COMBUSTION ENGINE.

Application filed May 31, 1922. Serial No. 564,889.

To all whom it may concern:

Be it known that I, LUDVIG A. LARSON, a citizen of the United States, residing at Summit, in the county of Roberts and State of South Dakota, have invented new and useful Improvements in Internal-Combustion Engines, of which the following is a specification.

This invention relates to internal combustion engines, and an object of the invention is to provide an engine designed for developing a maximum amount of power, in proportion to its size and weight, and also to provide an engine wherein there are no dead 10 or idle strokes in the cycle of operation of the engine, the said engine embodying opposed pistons moving synchronously so that when one is being operated under power or explosion stroke the other will be compressing 15 a new charge of combustible gas for explosion in its turn.

Another object of this invention is to provide an internal combustion engine as specified which is comparatively simple in construction, eliminating the use of cams, cam gears and the like and its construction.

Other objects of the invention will appear in the following detailed description taken in connection with the accompanying drawings wherein:

Fig. 1 is a longitudinal section through the improved internal combustion engine.

Fig. 2 is a fragmentary longitudinal section taken on the line 2—2 of Fig. 1.

Fig. 3 is a side elevation of the improved engine constructed in a V shape.

Referring more particularly to the drawings, the improved internal combustion engine comprises a pair of opposed cylinders 1 and 2, which are water jacketed as shown at 3 and which are carried by a suitable casting structure 4 embodying removable plates 5 by means of which access may be gained to the interior of the engine structure. A double piston 6 is reciprocably mounted in the cylinders 1 and 2 and comprises opposed piston ends 7 and 8 adapted to operate in the cylinders 1 and 2 respectively. The piston structure 6 is hollow or sleeve like, and it reciprocates over a valve core 9 which is anchored in any suitable manner in the cylinder structure and is provided with substantially L shaped passages 10 which have communication respectively with the cylinders 1 and 2 and with suitable valve chambers 11 which in turn have communication

with the intake manifold 12 of the engine structure. The double piston 6 is provided with a longitudinal slot 6' through which the manifold 12 extends and it is also provided with a slot 7' which receives therethrough the bolt 8' which serves to attach the stationary valve core 9 to the cylinder. The valves 13 which control the inlet of fuel into the passages 10 are mounted to be drawn inwardly to permit the inlet of gas by the suction created through the passages and the respective cylinders by movement of the pistons therein, and as the piston structure 6 reciprocates, that is when it moves upwardly as shown in Fig. 1 of the drawings, a charge of fuel is drawn into the piston end 7, where it is compressed as the piston moves downwardly under the explosion of a compressed charge in the explosion chamber 14. The charge of fuel which is compressed in the piston 7, passes from the interior of the piston 7 through the ports 15 and 16 into the by pass 17 and out of the by pass 17 through the port 18 into the cylinder structure where it is again compressed by the explosion of the compressed charge of fuel in the cylinder 2, which latter explosion acts upon the piston 8 for forcing it towards the stationary valve core 9 and consequently forcing the piston 7 away from the core 9. The piston 8 has a port 19 adapted to register with the port 20 which has communication with the by pass 21, to permit the passage of compressed gas from the interior of the piston 8 through the passage way 21 and its port 22 into the cylinder 2. The ports 19 and 20 are shown in registration in Fig. 1 of the drawings.

The piston structure 6 embodying the connected pistons 7 and 8 are connected by suitable connecting rods 24 to the crank shaft 25 which is rotatably supported in a suitable crank shaft housing 26. A suitable bearing extension 27 is formed on the water jacket 3 of the cylinder 2 and receives a portion of the crank shaft 25 therein. Spark plugs 28 of approved types may be located as found necessary or convenient for exploding the charges in the various cylinders and it is to be understood that piston rings of approved types are employed wherever necessary in the engine structure.

In Fig. 3 of the drawings the improved engine is shown as constructed in V type, however, it is to be understood that they may be used in single units or in multiple

thereof as desired, without departing from the spirit of this invention.

It is, of course, to be understood that the invention may be constructed in other manners and the parts associated in different relations and, therefore, I do not desire to be limited in any manner except as set forth in the claims hereunto.

Having thus described my invention what 10 I claim is:

In an internal combustion engine, a cylin-

der, a hollow piston mounted for reciprocation therein, a stationary valve core in said piston and provided with L shaped passageways opening out through its ends and 15 through its side intermediate its ends, an intake manifold communicating with the side openings of said passageways, said piston provided with a slot engaging over said

manifold.

In testimony whereof I affix my signature.

LUDVIG A. LARSON.
